PACKAGE FORMING MACHINE

Frederick E. Bickford, Westchester, N. Y.

Application May 1, 1946, Serial No. 666,270

11 Claims. (Cl. 93—47)

1

The present invention relates to a package forming machine and particularly to such a machine in which a package is formed from a sheet of thermoplastic material such as cellulose acetate or other thin moldable flexible material of like character.

In my copending application Serial No. 529,066, filed April 1, 1944, I described a packaging and package forming machine in which a scored and slotted blank was utilized to form a tray, two trays of slightly different dimensions being usable to form a complete package. The present machine is in many respects similar to that of the above mentioned copending application, differing therefrom primarily in that the blank utilized is not pre-formed but rather the acetate or like moldable material in sheet form is fed from a reel and formed into trays in the machine of this invention.

Furthermore, although the machine of the copending application can be utilized to form trays to ultimately be used as the halves of a complete package that machine was primarily designed to produce trays which were to be utilized as reinforcing ends for packages and the machine was consequently so designed as to permit severing the formed trays and adhering them to another and separate package forming sheet.

As will be clear from the above description of the similarities and differences of the two machines this application is a continuation in part of my copending application Serial No. 529,066.

In the present machine a sheet of material the width of which is equal to the width of the base plus twice the height of a package to be formed is taken from a reel and passed through the machine. During its passage through the machine the sides are folded upwardly as are the ends to form a traylike member, the corner folds being bent back along the sides of the tray and adhered thereto to provide reinforcing for the corners of the tray structure. As is obvious two trays of slightly different dimensions may be utilized to form a complete package, the smaller tray serving as the base and the larger as the cover.

It is an object of the present invention to form packaging trays from a sheet of thin thermoplastic material such as cellulose acetate or like moldable material.

It is a further object of the invention to provide a machine for producing such trays in which the folded corners are operated upon to crease them exactly and are then caused to be folded

2

back along the upstanding sides of the tray and adhered thereto.

It is another object of the invention to provide a machine for producing packaging trays which may be either manually or automatically operated.

It is a further object of the invention to provide means for stripping the formed trays from the plunger member of the machine after their formation.

Other objects and features of the invention will become apparent when the following description is considered in connection with the annexed drawings in which—

15 Figure 1 is a side elevation of the machine of my invention;

Figure 2 is a longitudinal cross section, the section being taken on the plane of the line 2—2 of Figure 1;

20 Figure 3 is a fragmentary longitudinal cross-section taken on the plane of the line 3—3 of Figure 1. This view shows a sheet of acetate or like thermoplastic material after it has been partially formed;

25 Figure 4 is a fragmentary cross-sectional view of the machine of Figure 1, this view being taken on the plane of the line 3—3 of Figure 1. It shows the positions of the parts after the plunger of the machine has descended somewhat further than was the case in Figure 3;

30 Figure 5 is a transverse cross-sectional view of the machine of Figure 1, the cross-section being taken on the plane of the line 5—5 of Figure 1;

Figure 6 is a view similar to Figure 5 but taken 35 on the plane of the line 6—6 of Figure 1;

Figure 7 is an enlarged fragmentary cross-sectional view showing particularly one of the early stages in the formation of the tray and the positions of the operating parts of the machine 40 at this stage. This view is taken on the plane of the line 7—7 of Figure 3 and shows the parts of the machine in the same positions as are indicated in that figure;

Figure 8 is an enlarged fragmentary cross-sectional view taken on the plane of the line 8—8 of Figure 4 and showing the positions of the various parts of the stage of operation depicted in Figure 4;

Figure 9 is a fragmentary horizontal view of 45 the machine, the view being taken on the plane of the line 9—9 of Figure 8 and showing particularly the mode of forming the corners of the packaging tray;

Figure 10 is a view similar to Figures 7 and 8 50 but showing the position of the various parts of

the machine at a later stage in the operation and specifically during the period when the folded corners of the packaging tray are being creased and formed into their final shape;

Figure 11 is a fragmentary horizontal cross-sectional view taken on the plane of the line 11-11 of Figure 10 showing the cooperation of certain rollers to crease the triangular corners of the tray;

Figure 12 is a view similar to Figures 7 through 10 but showing the parts of the machine when the plunger has descended still further and the formed corners have been bent back along the sides of the tray and adhered thereto to form the complete packaging tray; and

Figure 13 is a fragmentary cross-sectional view taken on the plane of the line 13-13 of Figure 12 showing more particularly the mode of bending the corners into their position against the sides of the tray.

Referring now to the drawings, the machine of the present invention comprises a channel-like member 10 having a slot 11 in the base thereof, this slot terminating at the points designated 12, Figure 2. Beneath the channel member 10 are a number of plates 13, 15 and 19 (Figures 5 and 6) which are arranged to provide a rectangular slot of substantially the same size as that in the channel 10 immediately beneath that in channel 10. Channel 10 is provided with a recessed undersurface above the slot formed by plates 13, 15 and 19 to provide for a bar 14 which slides into the recess from the right as seen in Figure 1 and forms a mold bottom during one of the stages of operation of the machine.

Beneath plate 13 is plate 15 which is recessed as indicated at 16 and provided with a rectangular slot 17. The recess 16 provides a guiding means for the bar 18 which moves in from the left as seen in Figure 1 and forms a bottom for the mold during another stage of the operation. Affixed to the plate 15 is a further generally channel-shaped plate 19 which completes the mold structure and is provided with a rectangular slot 20 through which the completed tray passes prior to its discharge.

Above and spaced from the channel member 10 there is mounted a plate 21 which is recessed on its undersurface as indicated at 22 of Figures 5 and 6 to provide a guide for a vacuum feed member 23 which member reciprocates being driven either manually or automatically. The vacuum feeding member 23, as is seen in Figure 2, comprises a generally rectangular plate provided with a plurality of passageways 24 and ports 25 through which a vacuum is drawn by means of the two-way valve 26 and the vacuum pump 27. As indicated in Figure 1, the member 23 may be horizontally reciprocated and may be moved from the position indicated in Figure 2, to a position in which its right hand edge lies beyond the right hand edge of the slot 11 in the channel member 10, an amount equal to the height of the tray.

The upper horizontal surfaces of the upstanding arms of channel member 10 are recessed at each side of the slot 11 as indicated at 28 (Figure 5) to form a space for entry of a sheet to be operated upon. Formed in the upper surfaces of the arms of channel 10 are ports 29 and passages 30 communicating therewith which are connected by means of the bores 31 in channel member 10 and the pipes 32, Figures 2 and 5, to the two-way valve 26 and through it to the vacuum pump 27.

Spaced above the plate 21 is a plate 33 which, together with the plate 21, is fastened to the

channel member 10 by means of the screws 34. Plates 21 and 33 are provided with rectangular slots which serve as guides for the plunger member 35 which is raised and lowered during the operation of the machine either by hand or automatically in any suitable manner.

Plunger means 35 is dimensioned in accordance with the thickness of the material of which the package tray is to be formed, that is, so dimensioned that when inserted in a molding chamber there will be a space between each plunger edge and its cooperating chamber side wall, which space will be equal to the thickness of the sheet material from which a package tray is formed.

At the ends of the channel member 10, the channel is filled in as, for example, by the blocks 36 (see Figure 7) which may be fastened within the channel in any suitable manner as by means of screws or by welding or may be made integral with the channel member 10. At the outer ends of the rectangular slot 11 the upstanding walls 10a of the channel 10 are provided with a narrow slot 37 (Figures 1 and 2), the outer sides of the slots being on a line with the blocks 36 so that there is formed an end forming surface for operation upon the ends of the blanks as will be described. The inner sides of the slots 37 form end surfaces on the side walls of the channel member 10 to cooperate with the surfaces of end forming plates 39 for forming the ends of the blank as hereinafter described. The blocks 36 are cut away as is indicated at 38 (see Figures 7, 8 and 10) to conform to the configuration of an end forming plate 39 which is pivotally mounted

on a shaft 40 extending between the upstanding arms of the channel 10. This plate 39 is pinned to the shaft 40 by means of the pin 41 and is spring urged to the position in which it is shown in Figure 7. A stop 42 is provided to limit the rotary movement of the plate 39 under urge of the spring 43. When the end forming plates 39 become parallel to the plunger ends they provide the ends of the mold. Fixed to the edge of the upstanding arms of the channel 10 adjacent each of the slots 37 is a resilient finger 44. Each of these fingers are designed to cooperate with a roller shortly to be described in order to press a triangular fold into the corners of the blank as the blank is operated upon by the plunger 35.

The slots 37 are widened at the inner sides thereof at the base of the channel member 10 to provide space for four rollers 45, which rollers cooperate with rollers 46 which are mounted in bores in the upstanding arm of the channel 10 adjacent the outer edge of the slot at each corner of the rectangular slot 11 in the channel 10. Additionally, a roller 47 is provided at each corner of the rectangular slot 11 lying above the roller 46 and cooperating with the respective resilient finger 44. Rollers 45, 46 and 47 are mounted on shafts 48, 49 and 50, respectively, these shafts extending through bores in the upstanding arms of the channel 10 to the exterior thereof. Mounted on the shafts 48, 49 and 50, respectively, are gears 51, 52 and 53. Gear 51 meshes with gear 52 and gear 51 is driven by a gear 54 mounted on a stub shaft 55 which is in turn rotatably mounted in the upstanding arm of the channel 10. Gear 53 meshes with a gear 56 mounted on a stub shaft 57 and gear 56 in turn meshes with gear 58 mounted on a stub shaft 59. Gears 54 and 58 mesh with a rack 60 which is fixed to the plunger 35 and moves therewith. The bottom plate 19 is recessed at the four places indicated

at 61 in Figure 1 to permit the racks 60 to descend to their lowermost limit of movement.

As has been indicated, the blanks are folded at their ends in such a manner as to produce a triangular-shaped extension of the ends which projects outwardly at each corner of the folded blank. In completing the formation of the tray structure, these triangular corners are folded back along the sides of the tray and adhered thereto. In order to accomplish this purpose there are provided four folding members 62 (see Figure 13) which members are mounted in the enlarged lower portions 38 of the slots 37. Each end folding member 62 is mounted on a shaft 63 which extends downwardly through the plates 15 and 19 and has mounted on its outer end a gear 64. Each gear 64 meshes with a gear 65 which is mounted on a shaft 66 which extends upwardly through the plates 19 and 15, the arms of the channel member 10 and the plates 21 and 33. On each shaft 66 between the plates 21 and 33 is a gear 67, these gears being fixed for rotation with their respective shafts 66. Each gear 67 meshes with a gear 68 mounted on a short shaft 69 extending between plates 21 and 33. Two of the gears 68 mesh directly with a gear sector 70 made integral with the collar 71 fixed to a shaft 72 which is supported in the plates 21 and 33. The remaining two gears 68 mesh with gears 73 which are mounted on stub shafts in the same manner as are gears 68 and in turn mesh each with one of the two gear sectors 70. Due to the interposition of the additional idler 73 at the diagonal corners of the machine, the end folding members 62 are caused to move in the correct direction to fold the triangular extensions of the end of the folded blank against the sides of the blank. The shafts 72 may be oscillated to cause this result in any suitable manner as, for example, by means of the helically slotted collars and pins which are illustrated in my above mentioned co-pending application. Whatever means is used to oscillate these shafts is, of course, operated in proper timed relationship to the remaining operations so that the extensions of the ends of the blank are folded against the sides at the proper moment.

A knife blade 75 is mounted adjacent to the plunger 35 and is guided by slots in the plates 21 and 33, as seen particularly in Figures 7 and 8. The blade 75 is mounted in any suitable manner as, for example, by means of the block 76 and cap block 77 which are vertically reciprocable in any suitable manner as by means of a manually operated lever or bellcrank. Cooperating with the blade 75 is a shearing edge 78 which is mounted in a recess in the top of the left hand one of the blocks 36 and which is adjustable due to the use of a screw 79 in a groove in the shearing edge (Figure 7). As is clearly indicated in Figures 7 through 10, the knife blade and shearing edge 78 are so located as to sever the proper amount of material to form a blank from which trays are molded.

In the preferred form of my invention the plunger 35 is provided with passageways 80 and ports 81, these ports being arranged on the bottom surface of the plunger and in such position that application of pressure fluid to the passageways 80 will cause the formed tray to be expelled from the plunger. The trays removed from the plunger may be received upon a belt such as is indicated in dotted lines in Figure 1 and designated 82, this belt being formed of chain links which are rectangular in shape and

of a size slightly greater than that of the trays being formed. Each of these chain links has a perforated bottom, the perforations being shown at 79 (Fig. 1), and since the chain is adapted to be moved intermittently, the perforations in the bottom of the links may be in alignment with exhaust ports 83 in the upper surface of a plate 84 during the time when the chain 82 is stationary. Thus by a combination of pressure on the inner surfaces of the bottoms of the formed trays and suction on the outer surfaces of the bottom, the formed trays are caused to be removed rapidly from the plunger 35 and to be seated within the rectangular chain links.

The foregoing has described the major features of construction of the machine. The remaining features will be described during the following description of the operation of the machine.

A roll of cellulose acetate or like thermoplastic material of proper width and having the requisite qualities of flexibility and moldability is mounted on a suitable reel, not shown, and the material designated 85 (Figure 1) is positioned beneath the vacuum registration plate 23. The valve 26 is then operated to cause a suction to be applied to the material 85 through the ports 25 in member 23. While the suction continues to be applied member 23 is moved manually or in any suitable automatic manner to the right as seen in Figures 1 and 2, until it reaches the right hand end of the recess 22 in the plate 21. At this time the member lies in a position such that the central rectangular portion of the sheet of material is directly above the slot 11 in the base of the channel member 10 and in position such that the sides of the sheet are above the recesses 28 in the upstanding arms of the channel member 10.

Upon arrival of the member 23 at this position, the valve 26 is operated to release the suction from the plate 23 and to apply suction to the pipes 32, passages 31 and 30 and ports 29 to the lower surfaces of the sides of the sheet 85. Next the plate 23 is moved to the left and into position to pick up a new length of material and move it into position to be operated upon. Then the knife blade 75 is moved downwardly and, cooperating with the shearing edge 78, severs the positioned sheet of material from the roll. Next plunger 35 descends and comes into contact with the central rectangular portion of the severed sheet causing the sides of the sheet to fold upwardly. At the same time the ends of the blank are caused to be folded upwardly by cooperation between the ends of the plunger 35 and the face of the forming plate 39. Thus when the plunger has descended to the position illustrated in Figures 3 and 7, the sides of the blank as well as the ends extend upwardly at substantially a 45° angle and a triangular fold, indicated at 86 in Figure 3, is formed at each corner of the blank.

Further descent of the plunger 35 brings about rotation of the end forming plate 39 and causes the sides and ends of the blank to extend upwardly at right angles to the base thereof, the triangular folds 86 extending into the slots 37, as is best seen in Figures 9 to 11. Shortly thereafter these triangular folds 86 are pressed between the end forming plates 39 and the resilient fingers 44 thereby causing the fold line to be pressed into the material. Continued descent of the plunger brings the folded triangular corners 86 between the ends of the resilient fingers 44 and the rollers 47 and thus increases the creasing action. At this time, of

course, the rollers 47 are rotating due to the movement of the racks 60 and the action thereof on the gear trains previously described. Next the plunger descends still further and carries the triangular folds 86 between the pairs of rollers 45 and 46 completing the creasing of the fold line of these triangular corners, the rollers 45 and 46 being rotated under drive of the racks 60. At about this time, the descent of the plunger 35 brings the base of the partially formed tray against the heated bottom bar or mold member 14 which at this time is in its left hand position having been driven there by means of the action of the gear 87 on the rack teeth 88 formed on the lower surface of the bar 14. Gear 87 may be driven in any suitable manner as, for example, by means of a crank or automatically, but in any event is moved in timed relationship to the operation of the other machine parts.

As has been stated, the bar 14 is heated so that the formed base edges of the tray are set in or molded in their desired right angle position. Shortly after this the gear 87 is operated to move the bar 14 to the right exposing the rectangular slot in the plate 13. Shortly after this the plunger 35 again descends, the rollers 45 and 46 resume their rotation, the final creasing of the fold lines is effected, and the corners 86 pass from between the rollers 45 and 46. Following this, the descent of the plunger is again halted by the bar 18 which is similar to the bar 14 and is similarly driven by means of rack teeth 89 on the bar and cooperating gear 90.

At this stage the partially formed tray is in position to be operated upon by the corner folding members 62 which, as is clearly indicated in Figure 13, rotate from their normal position, shown in dotted lines in Figure 13, to their operated or full line position and thereby cause the triangular corners to be folded back against the sides of the tray members and adhere thereto.

In order to insure such adhesion, the folding members 62 may be heated in any suitable manner, such for example as by the use of electrical resistance heaters, as shown in Figure 1, the mold and the folding members 62 then being heated by conduction from the heated bottom bar or mold bottom 18. As indicated, an electrical resistance heater 18a is utilized to supply heat to the bottom bar 18, this heater being connected in the usual manner to any suitable power source.

After adhesion of the corners, the bar 18 is moved to the left and the plunger caused to descend through the plate 15 and the base plate 19 and into the position indicated in the dot-dash lines in Figure 1. When the plunger is seated within one of the rectangular links of the chain 82, its descent is terminated and pressure is applied to the ports 81 while at the same time suction is applied through the exhaust ports 83 and perforations 79 in the bottom of the link to release the formed tray from the plunger 35. Immediately thereafter the plunger 35 is caused to rise to its uppermost position, the valve 26 is again operated to cause application of suction to the plate 23, and a new sheet of material is fed to the machine and the operations described above repeated to form another in the succession of trays.

While I have described a preferred form of my invention it will be understood that various modifications thereof are possible and I do not desire, therefore, to be restricted to the particular details shown and described, but only to the scope of the appended claims.

What is claimed is:

1. In a device for making package trays from thermoplastic sheet material, in combination, a mold member having a removable bottom, 5 standing sides extending above said bottom, upstanding end members extending across said side members and slightly spaced therefrom, a reciprocable vacuum registering member mounted to move above the molding chamber formed by said bottom member and side and end members, means for applying a vacuum to said reciprocable member, means for mounting a roll of flexible moldable material in position to be registered on said reciprocable member, means in said mold 15 side walls for drawing a vacuum therethrough, and means for releasing moldable material carried by said reciprocable member from said member while in position above said mold and for simultaneously applying a vacuum to said mold 20 side walls to register the flexible mold material thereon.

2. In a device for making package trays from thermoplastic sheet material, in combination, a mold member having a removable bottom, 25 standing sides extending above said bottom, upstanding end members extending across said side members and slightly spaced therefrom, a reciprocable vacuum registering member mounted to move above the molding chamber formed by said bottom and side and end members, means for applying a vacuum to said reciprocable member, means for mounting a roll of flexible moldable material in position to be registered on said reciprocable member, means in said mold side walls for drawing a vacuum therethrough, means for releasing moldable material carried by said reciprocable member from said member while in position above said mold and for simultaneously applying a vacuum to said mold side walls to register the flexible moldable material thereon, and means for severing a portion of said moldable material equal in length to the length plus twice the height of the tray to be formed from the sheet.

3. In a device for making package trays from thermoplastic sheet material, in combination, a 45 mold member having a removable bottom, upstanding sides extending above said bottom, upstanding end members extending across said side members and slightly spaced therefrom, means for feeding a sheet of moldable material above the molding chamber formed by said bottom and side and end members, means for severing a length from said sheet equal to the length plus twice the height of the tray to be formed, means for forcing the severed sheet into said chamber 50 to fold the sides and ends of the severed portion upwardly to form a tray like member having the extremities of its ends extending into the spaces between the mold sides and mold ends, and means adjacent to said space for creasing the folds formed at the extremities of said ends of said tray like member.

4. In a device for making package trays from thermoplastic sheet material, in combination, a 65 mold member having a removable bottom, upstanding sides extending above said bottom, upstanding end members extending across said side members and slightly spaced therefrom, means for feeding a sheet of moldable material above the molding chamber formed by said bottom and side and end members, means for severing a length from said sheet equal to the length plus twice the height of the trays to be formed, means for forcing said severed length into said chamber 70 to fold the sides and ends of the severed portion

upwardly to form a tray like member having the extremities of its ends extending into the spaces between the mold sides and mold ends, means adjacent to said space for creasing the triangular folds formed at the extremities of said ends of said tray like member, said last mentioned means comprising rollers adjacent one side of the extremity of each end, and resilient fingers adjacent said space and cooperating with said rollers.

5. In a device for making package trays from thermoplastic sheet material, in combination, a mold member having a removable bottom, upstanding sides extending above said bottom, upstanding end members extending across said side members and slightly spaced therefrom, means for feeding a sheet of moldable material above the molding chamber formed by said bottom and side and end members, means for severing a length from said sheet equal to the length plus twice the height of the tray to be formed, means for forcing said severed length into said chamber to fold the sides and ends of the severed portion upwardly to form a tray like member having the extremities of its ends extending into the spaces between the mold sides and mold ends, means adjacent to said space for creasing the triangular folds formed at the extremities of said ends of said tray like member, said last mentioned means comprising rollers adjacent one side of the extremity of each end, and resilient fingers adjacent said space and cooperating with said rollers, and additional means for further impressing the crease in the extremities of the ends of said tray like members, said additional means comprising pairs of rollers located on either side of said spaces, said pairs of rollers cooperating with each other to press the extremities of the ends of the tray like members therebetween.

6. In a device for making package trays from thermoplastic sheet material, in combination, a mold member having a removable bottom element, upstanding sides extending above said bottom element, upstanding end members extending across said side members and slightly spaced therefrom, end forming plates pivotally mounted in said end members, means for feeding a sheet of moldable flexible material into position above the mold chamber formed by the said bottom member and side and end members, means for severing a portion from said sheet, said portion having a length substantially equal to the length plus twice the height of the tray to be formed, means for vacuum registering said portion of said sheet on the upstanding side walls of said mold chamber, plunger means substantially filling said mold chamber, said plunger means cooperating with said upstanding side walls and said end plates to cause folding of the side and end edges of the severed portion of said sheet upwardly to form a tray like member, said end forming plates moving about their pivots as the plunger descends into the mold chamber until they become parallel with the sides of said plunger means and thereby press the moldable material against said plunger.

7. In a device for making package trays from thermoplastic sheet material, in combination, a mold member having a removable bottom, upstanding sides extending above said bottom, upstanding ends extending across said sides and being slightly spaced therefrom, plates mounted in said upstanding ends, said plates being generally T-shaped, means for feeding a sheet of material above the molding chamber formed by said bottom, side and end elements, plunger means

of a cross-sectional area substantially equal to that of the mold chamber for forcing said moldable material into said mold chamber to thereby cause the sides and ends of said sheet to be folded upwardly and to form a triangular fold at each extremity of each end of the tray formed thereby, said triangular folds extending into the space between said mold side members and end members, means adjacent each triangular crease for pressing the crease, each said means comprising a resilient finger and a roller cooperating therewith, and means for driving said rollers, said means comprising a gear train and a cooperating rack, said racks being mounted on said plunger means for movement therewith.

8. In a device for making package trays from thermoplastic sheet material, in combination, a mold chamber having a removable bottom, upstanding sides extending above said bottom, upstanding ends extending across said sides and being slightly spaced therefrom, plates mounted in said upstanding ends, said plates being generally T-shaped, means for feeding a sheet of material above the molding chamber formed by said bottom, side and end elements, plunger means of a cross-sectional area substantially equal to that of the mold chamber for forcing said moldable material into said mold chamber to thereby cause the sides and ends of said sheet to be folded upwardly and to form a triangular fold at each extremity of each end of the tray formed thereby, said triangular folds extending into the space between said mold side members and end members, means adjacent each triangular crease for pressing the crease, additional means adjacent each crease for further pressing the said crease, said additional means comprising a pair of rollers situated on each side of each said end of each extremity, said rollers of both said first and said additional creasing means being driven by said plunger means.

9. In a device for making package trays from thermoplastic sheet material, in combination, a mold member having a removable bottom, upstanding sides extending above said bottom, upstanding ends extending across said sides and being slightly spaced therefrom, plates mounted in said upstanding ends, said plates being generally T-shaped, means for feeding a sheet of material above the molding chamber formed by said bottom, side and end elements, plunger means of a cross-sectional area substantially equal to that of the mold chamber for forcing said moldable material into said mold chamber to thereby cause the sides and ends of said sheet to be folded upwardly and to form a triangular fold at each extremity of each end of the tray formed thereby, said triangular folds extending into the space between said mold side members and end members, means adjacent each triangular crease for pressing the crease, means for folding said triangularly creased end extremities against the side walls of the tray like member, heating means for adhering said folded extremities to said side walls and for setting all folds of material, said plunger means driving said formed tray outwardly through the bottom of said mold member, and means for removing the formed tray from said plunger means, said last mentioned means comprising a vacuum element on which the plunger means deposits the formed tray.

10. In a device for making package trays from thermoplastic sheet material, in combination, a mold member having a removable bottom, up-

standing sides extending above said bottom, upstanding ends extending across said sides and being slightly spaced therefrom, plates mounted in said upstanding ends, said plates being generally T-shaped, means for feeding a sheet of material above the molding chamber formed by said bottom and side and end elements, plunger means of a cross-sectional area substantially equal to that of the mold chamber, for forcing said moldable material into said mold chamber to thereby cause the sides and ends of said sheet to be folded upwardly and to form a triangular fold at each extremity of each end of the tray formed thereby, said triangular folds extending into the space between said mold side members and end members, means adjacent each triangular crease for pressing the crease, additional means adjacent each crease for further pressing the said crease, said additional means comprising a pair of rollers situated on each side of each said end of each extremity, said rollers of both said first and said additional creasing means being driven by said plunger means, means operable upon said plunger means seating against said removable bottom member of said mold for folding the said triangularly creased extremities of the ends of said sheet against the sides of the formed tray like member, means for removing said bottom member from said mold, an additional mold chamber mounted beneath said main mold chamber, said additional mold chamber having a removable bottom member, said plunger means being operable to position said formed tray against said additional removable mold bottom, heating means for causing adherence of said folded triangularly creased extremities to the sides of the formed tray and for setting all folds, means for removing said second removable bottom member, said plunger means moving downwardly to remove the formed trays from the entire mold structure, and means to remove the formed tray from the plunger means, said last mentioned

means comprising a vacuum element on which the plunger deposits the formed tray.

11. In a device for making thermoplastic package trays from sheet material, in combination, a molding chamber having a removable bottom, upstanding sides extending above said bottom, upstanding end members extending across said side members and spaced therefrom a distance equal to the thickness of the sheet material utilized, means for feeding a sheet of material above the molding chamber formed by said bottom and side and end members, means for severing a length from said sheet equal to the length plus twice the height of the tray to be formed, means for forcing the severed sheet into said molding chamber to fold the sides and ends of the severed portion upwardly to form a tray-like member having the extremities of its ends extending into the spaces between the mold sides and the mold ends, means for creasing the triangular folds formed at the extremities of said ends of said tray-like member, and means for heating at least one element of said molding chamber to set the creases formed in said sheet material.

FREDERICK E. BICKFORD.
